UNITED STATES PATENT OFFICE.

HENRY JURGENS, OF DENVER, COLORADO

ICE-CREAM FREEZER.

1,035,016.

Specification of Letters Patent. Patented Aug. 6, 1912.

Application filed October 12, 1911. Serial No. 654,231.

To all whom it may concern:

Be it known that I, HENRY JURGENS, a citizen of the United States, and a resident of Denver, in the county of Denver and 5 State of Colorado, have invented a new and Improved Ice-Cream Freezer, of which the following is a full, clear, and exact description.

My invention relates to an ice cream 10 freezer, and an object of my invention is to provide a stationary can into which the cream may be fed continually without interrupting the operation of the movable parts, and a further object of my invention 15 is to provide in addition to the ordinary form of dasher, an agitator for the ice and brine.

With the above and other objects in view, as will more fully hereinafter appear, the 20 present invention consists in certain novel details of construction and arrangement of parts hereinafter fully described, illustrated in the accompanying drawings, and more particularly pointed out in the appended 25 claims.

Reference is to be had to the accompanying drawings, forming a part of this specification, in which similar characters of reference indicate corresponding parts in both 30 the views, and in which—

Figure 1 is a vertical transverse section taken through a preferred embodiment of my invention, and Fig. 2 is a similar view of the agitating drum.

The tub 3 of any suitable construction, 35 has immovably positioned centrally therein, a cream can 4 of general cylindrical form, the top 5 of which has an inlet 6 closed by means of a cap 7. An outlet 8 extends 40 through the bottom 9 and through the bottom 10 of the tub 3. This outlet is closed by any suitable means, as, for instance, a screw cap 11. Centrally journaled within the can is a suitable form of dasher 12, rigidly mounted upon the upper end of which 45 is a bevel gear 13 adapted to engage the vertically disposed bevel gear 14 on the inner end of the shaft 15, which shaft is actuated by a crank 16 or other suitable rotating 50 means. These actuating members are carried by a suitable form of bridge 17, one end of which is pivoted at 18 to the upper edge of the tub 3, and the opposite end of which is fastened to the tub by a jam nut 19 55 or other suitable holding means.

Rigidly mounted upon the shaft 15 is a relatively large bevel gear 20, adapted to engage an annular gear 21 integral with the top 22 of the cylindrical agitating drum 23, the under surface of the top of which drum 60 has a guideway 24 resting on a rim 25 projecting from the top 5 of the can 4. The drum 23 is concentric with the can 4 and is spaced apart from said drum by means of spirally formed inwardly-projecting ribs 26. 65 This drum has numerous apertures 27 extending therethrough.

It will be seen by the above outlined construction, that the unfrozen cream is fed through the inlet 6 into the can 4 while the 70 freezer is in operation, the dasher rotating in one direction as is common with devices of this character, while the agitating drum 23 is rotated in the opposite direction to agitate the ice and brine within the tub and 75 surrounding the can 4. When the cream has reached a sufficient degree of consistency, it is withdrawn through the outlet 8 and additional unfrozen cream added through the inlet 6, and the operation continued. 80

Having thus described my invention I claim as new and desire to secure by Letters Patent:

1. In an ice cream freezer, a tub, a cream can immovably mounted in said tub, a drum 85 within said tub surrounding said can and carried thereby, a dasher within said can, an actuating shaft carried by said tub, and gear connections with said drum and said dasher rotating said dasher in one direction 90 and said drum in the opposite direction.

2. In an ice cream freezer, a tub, a cream can immovably mounted in said tub, a drum within said tub surrounding said can and carried thereby, a dasher within said can, 95 an actuating shaft carried by said tub, gear connections with said drum and said dasher rotating said dasher in one direction and said drum in the opposite direction, and ribs on said drum spacing said drum from said 100 can and agitating the brine and ice within said tub.

In testimony whereof I have signed my name to this specification in the presence of two subscribing witnesses.

HENRY JURGENS.
